CLAIM

The ornamental design for a toy, as shown and described.

DESCRIPTION

FIG. 1 is a top and front, perspective view of a toy showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view.

The features shown in broken lines are portions of the toy forming no part of the claimed design. The bolded broken lines between the solid and broken line portions or the wires indicate the bounds of the claimed design and otherwise form no part of the claimed design.
